(57) **CLAIM**

The ornamental design for a door rail end cap, as shown and described.

DESCRIPTION

FIG. 1 is a top, front, left side perspective view of a door rail end cap;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a top, front, left side perspective view of the door rail end cap shown in an environment of use. The broken lines shown in FIGS. 1-7 illustrate portions of the door rail end cap that form no part of the claimed design. The additional broken lines shown in FIG. 8 illustrate environment that forms no part of the claimed design.

1 Claim, 4 Drawing Sheets
